CLAIM

I claim the ornamental design for a skincare device, as shown and described.

DESCRIPTION

FIG. 1 is a perspective view of a skincare device showing my new design.

FIG. 2 is a top view of the skincare device.

FIG. 3 is a bottom view of the skincare device.

FIG. 4 is a rear view of skincare device.

FIG. 5 is a front view of the skincare device.

FIG. 6 is a right side view of the skincare device; and, FIG. 7 is a left side view of the skincare device.

The letters FOREO shown in dashed lines are for the purposes of illustrating environmental structure which form part of the claimed design.
